MOISTENING DEVICE

Herbert William Harrington, London, England

Application November 19, 1932, Serial No.
643,547, and in Great Britain October 22,
1931

3 Claims. (Cl. 91—51)

This invention relates to improvements in apparatus for moistening the fingers, gummed paper, envelope flaps, stamps, and the like, the closure of, and distribution by same, and consisting of a hollow container of any material with an orifice at the top and a soft, hollow, spherical, elongated or other shaped rubber body inserted therein.

In this type of moistener water is introduced into the container through the orifice at the top by keeping the body depressed. On releasing same it rises in the water by virtue of its buoyancy and effectively closes the orifice of the container the circumference of which is slightly smaller than that of the body. It will be clearly seen that the closure of the opening is obtained without the help of springs of any kind or by any mechanical aid. The body besides closing the orifice, also provides the means of supplying the water for moistening purposes without inverting the apparatus, as it is free to revolve and in so doing presents a freshly wetted portion of its surface, the water adhering thereto and being transmitted solely by surface tension.

In known forms of this type of moistener the ball is depressed into the containing vessel when used creating splashing and it is the chief object of my invention to overcome this drawback and provide resistance to depression whilst operating the device.

In the form of the invention herein described, the body referred to will be taken as a sphere or ball.

To prevent water from flowing over the outside of the container in the event of the ball being depressed therein or when draining from the surface of the ball after revolving, a portion of the rim of the circular orifice (the same being circular to conform with the spherical shape of the body used in this instance) is turned inwards and downwards so that the line of contact between the ball and the rim of the orifice is lower than the surrounding part of the container, thus forming with the ball in its floating position an annular channel which will accommodate any such water draining from it until the next revolution of same, when part will be redistributed to the surface thereof and part returned to the container, or in the unlikely case of depression of the ball to the bottom of container, will enable the water to rise without overflowing. The inwardly turned rim also keeps the ball clear of the sides of the container thus preventing interference with its free movement in any direction.

The rim of the container is constructed in such

manner as to present a sharply defined edge to the ball which is of a soft nature, and when pressure is applied to the latter the initial effect is to form a slight indentation in the surface of the ball instead of depressing it into the container, thus causing it to expand outwards and pressure to be exerted on the rim of the container, the edge of which cuts into the ball; this expansion prevents the air escaping past the ball from the container which in turn prevents the ball from being depressed into the container without considerable force being used, as it will be seen that the harder the ball is depressed, the greater the reaction by it on the rim of the container and the more effective closure of same.

In order to assist the foregoing description I will now describe my invention with reference to the accompanying drawing.

Fig. I is a vertical section through the diameter of the device; Fig. II is a plan view and Fig. III is an enlarged section of the rim in contact with the ball.

In this embodiment of the invention, A is the soft hollow rubber ball floating in water C, contained in the vessel B. The point of contact between the ball A and the rim E of the orifice is at D. The annular channel formed by the downwardly and inwardly turned rim E of the container and the ball when floating is at F.

It will be seen from Fig. III that the contact between the rim E and the ball A is practically a "line contact" (but this is not an essential) and is obtained by making the edge of the rim E of wedge shaped section, as shown, presenting the apex of same to the ball in order to make the closure more positive when the ball A is depressed causing it to exert pressure on the rim E, and to reduce friction when revolving.

It will also be seen in Fig. I how the inwardly turned rim E keeps the ball A clear of the sides of the container B when floating in water C.

The device, employing in this case a spherical ball A is able to be operated from any direction, and the continuous rotation against the sharp edge of rim E keeps the floating body free from any deposits thereon.

The orifice of the container being constantly and automatically closed, evaporation is kept at a minimum, the undesirable ingress of dirt is prevented, and the water therein cannot be spilt by normal movement of the device.

The surface of the floating body is preferably of a rough or matt finish to facilitate the adhesion of the water thereto and to ensure it being evenly transmitted.

The inclusion of a disinfectant in the water used keeps the device sweet and causes it to act as a deodorizer.

Having now particularly described and ascertained the nature of my said invention, and in what manner the same is to be performed, I declare that what I claim is:—

1. A moistening device consisting of a container for liquid, said container having a rim defining an orifice, said rim being inturned and projecting downwardly providing an annular air pocket remote from said orifice but communicat-

ing with said liquid, a spherical body in said container making contact with the inner peripheral edge of said inturned rim, said liquid and rim constituting the sole support for said body when the device is in use.

2. A device according to claim 1 characterized by said rim having a wedge-shaped section contacting said body.

3. A device according to claim 1 characterized by said body being hollow and of soft rubber with a roughened or mat surface.
